FUEL AGITATOR

Henri A. Ridet, Paris, France, assignor to Société Anonyme: Fours et Appareils Stein, Paris, France, a corporation of France

Application October 2, 1934, Serial No. 746,595
In France October 23, 1933

1 Claim. (Cl. 110—44)

This invention relates to furnaces and has for its object to provide an improved fuel agitator designed for use with furnaces in which the fuel is fed from underneath the firebed.

5 A further object of the invention is the provision of a fuel agitator and operating means therefor by which an oscillating movement is imparted to the agitator to improve the combustion of the fuel.

10 A further object of the invention is the provision of means for conducting a fluid cooling medium to the fuel agitator to prevent the latter from becoming overheated.

15 In the accompanying drawing wherein an approved embodiment of the invention is illustrated:

Figure 1 is a view partly in side elevation and partly in section showing the invention applied to an underfeed furnace.

20 Fig. 2 is a fragmentary top plan view showing the operating mechanism for imparting oscillating movement to the fuel agitator.

25 Referring to the drawing in detail, the fuel agitator is indicated at 5 and includes a tubular body member 5^a mounted in a bearing 6^a supported on a spring 6^b arranged in the front wall 6 of the furnace and extending exteriorly of the latter. The inner end of the tubular member 5^a is located immediately above the retort 7 and is mounted for oscillating movement about its longitudinal axis in a bearing 8.

30 The portion of the agitator located above the retort is formed with radially projecting tubular fingers 9 and is situated between the tuyère openings 1^a in the retort.

35 A conduit 10 for a fluid cooling medium is located in coaxially spaced relation within the tubular member of the agitator. The conduit 10 is provided with branch conduits 11 which extend into the tubular fingers 9 and terminate in spaced relation to the ends thereof to permit the free 40 passage of cooling medium.

Externally of the furnace, the tubular member 5^a of the agitator and the conduit 10 are suitably connected at 5^a and 10^a respectively in a fluid circuit whereby a fluid cooling medium is circulated through the tubular member and conduit and the passages between the latter as well as between the branch conduits 11 and inner surfaces of the tubular fingers 9.

5 The end of the tubular member 5^a of the agitator located externally of the furnace is supported in a bearing 12 and is provided with a gear 13 meshing with a second gear 14 fixed to a shaft 15. The shaft 15 is mounted in a bearing 16 and is provided with an arm 17 connected by a link 18 with a crank pin 19 on a driving shaft 20.

10 The shaft 20 is preferably connected with a power driven part of the furnace whereby rotary movement is imparted thereto and in operation the motion is transmitted to the shaft 15 through the crank pin 19, link 18 and arm 17, thereby 15 producing an oscillating movement of the fuel agitator 5. The circulation of the cooling fluid through the inner end of the agitator and the tubular fingers 9 thereof insures proper cooling of the agitator and prevents damage thereto by 20 exposure to the heat.

What I claim is:

30 In combination, an underfeed furnace including a retort, a fuel agitator including a tubular member extending through a lateral wall of the furnace and immediately above the retort and mounted for oscillation about its longitudinal axis, tubular fingers carried by and communicating with said member and extending into the retort, means conducting a cooling fluid to said fingers, a gear on said member exterior to the furnace, a second gear meshing with said first gear, a crank connected with said second gear so as to impart an oscillatory motion thereto.

HENRI A. RIDET.
